UNITED STATES PATENT OFFICE.

EDGAR FOSTER, OF VICKSBURG, MISSISSIPPI.

RAILROAD-SIGNAL.

1,269,919.

Specification of Letters Patent. Patented June 18, 1918.

Application filed September 16, 1916. Serial No. 120,492.

To all whom it may concern:

Be it known that I, EDGAR FOSTER, a citizen of the United States, residing at Vicksburg, in the county of Warren and State of

5 Mississippi, have invented certain new and useful Improvements in Railroad-Signals, of which the following is a specification, reference being had therein to the accompanying drawing.

10 This invention relates to railroad signals and has for its object the production of a simple and efficient means for automatically closing an electric signal circuit when a train or car passes over a given point of the 15 railroad track.

Another object of this invention is the production of a simple and efficient circuit closing means for actuating the desired signal.

20 With these and other objects in view, this invention consists of certain novel constructions, combinations and arrangements of parts as will be hereinafter more fully described and claimed.

25 In the drawings:

Figure 1 is a top plan view of the signal apparatus.

Fig. 2 is a central section taken on line 2—2 of Fig. 1.

30 Fig. 3 is a section taken on line 3—3 of Fig. 1.

Fig. 4 is a section taken on line 4—4 of Fig. 1.

35 Fig. 5 is a section taken on line 5—5 of Fig. 1.

Fig. 6 is a section taken on line 6—6 of Fig. 1.

Fig. 7 is a section taken on line 7—7 of Fig. 3.

40 Fig. 8 is a detail perspective of the contact blocks carried by the signal casing.

Fig. 9 is a section taken on line 9—9 of Fig. 3.

By referring to the drawings, it will be 45 seen that 1 designates the longitudinal rails of the railroad track which is supported upon the usual ties 2. A plurality of spring supporting blocks 4 are carried by the ties and support springs 5 engaging at their outer ends a flange engaging plate 6. The

wardly curved outer edge 9 as is illustrated clearly in Fig. 5 of the drawings, the plate 6 being adapted to fit snugly against the side of the tread of the rail 1.

60

A roller supporting bracket 10 is carried by one of the ties 2 and also a supporting roller 11, which roller 11 constitutes a rest for the rear end of the channel plate 6 as illustrated in Figs. 2 and 6 of the drawings. 65 A supporting link or arm 12 is secured between the ears 13 of the channel plate 6 and this arm 12 is carried by an operating shaft 14. The shaft 14 passes through the supporting brackets 15 as illustrated in Fig. 70 3 and a contact closing arm 16 is carried by the outer end of this shaft 14. The shaft 14 is formed of a plurality of sections, one section being provided with an enlarged head 17 in which one end of the opposite 75 section is adapted to fit as shown clearly in Fig. 9. A coil spring 18 is mounted upon one of the sections of the shaft 14 and is adapted to normally hold the contact arms 16 in an inoperative position. One end of 80 the spring 18 engages the cam 15' as shown at 26 in Fig. 3, while the opposite end of the spring extends into the head 17, as shown at 27 in Figs. 1 and 3.

85 A plurality of contact blocks 19 are carried within the signal casing 20, which casing is formed of wood or similar non-conductive material, and this signal casing 20 supports a light 21 and an audible signal such as a bell 22.

90 A battery 23 is positioned or supported within the casing 20 and is electrically connected to the respective contact points 24 and 25, light 21 and bell 22 so as to energize the signals when the contact arm 16 is thrown into engagement with the contact blocks or points 24 and 25. It, of course, should be understood that the signal, light and bell can be placed in any desired position with respect to the switch throwing plate 6, to suit the desire of the 95 operator. The signal, light and bell are, of course, intended to be placed at a point where the signal is to be given, such as a railroad crossing or the like.

100

What is claimed is:

1. In a signal operating mechanism of the character described, the combination of a shaft, means for normally retaining said shaft in a set position, an arm keyed to said shaft, a roller, a plate pivotally connected 110 to said arm and resting upon said roller, whereby when said plate is depressed it may

55 the wheel traveling over the rails 1 is adapted to fit. The plate is provided with an out-

ride over said roller for swinging said arm and turning said shaft.

2. In a signal operating mechanism of the character described, the combination of a shaft, means for normally retaining said shaft in a set position, an arm keyed to said shaft, a roller, a plate pivotally connected to said arm and resting upon said roller, whereby when said plate is depressed it may 5 ride over said roller for swinging said arm and turning said shaft, and springs engaging said plate for yieldably retaining the same in a set position.

3. In a signal operating mechanism of the character described, the combination of a shaft, means for normally retaining said shaft in a set position, an arm keyed to said shaft, a roller, a plate pivotally connected to said arm and resting upon said roller, 10 whereby when said plate is depressed it may ride over said roller for swinging said arm and turning said shaft, plates positioned beneath said first-mentioned plate and having sockets formed therein, springs carried with- 15 in said sockets, whereby said springs will be held against displacement, said springs engaging said first-mentioned plate, thereby yieldably retaining said first-mentioned plate in a set position.

4. In a signal operating mechanism of the character described, the combination of a shaft, means for normally retaining said shaft in a set position, an arm keyed to said shaft, a roller, a plate pivotally connected to said arm and resting upon said roller, whereby when said plate is depressed it may 20 ride over said roller for swinging said arm and turning said shaft, plates positioned beneath said first-mentioned plate, 25 and having sockets formed therein, springs carried within said sockets, whereby said springs will be held against displacement, said springs engaging said first-mentioned plate, thereby yieldably retaining said first-mentioned plate in a set position, and said 30 first-mentioned plate having a longitudinally extending concaved portion adapted to receive the flange of a wheel, whereby when said first-mentioned plate is depressed it will 35 be held against side displacement.

5. In a signal operating mechanism of the character described, the combination of a roller, a plate resting upon said roller, said plate being adapted to be connected to a signal, said plate being adapted to be depressed so as to ride over said roller and operate the signal, springs engaging said plate for yieldably holding the same in a set position, said plate having a longitudinally extending concaved portion, whereby 40 as the plate is depressed the flange of a wheel fitting in said concaved portion will hold said plate against side displacement, plates positioned beneath said first-mentioned plate and having sockets formed 45 therein, springs carried by said sockets, whereby said springs will be held against displacement, said springs engaging said first-mentioned plate, thereby yieldably retaining said first-mentioned plate in a set 50 position.

6. In a signal operating mechanism of the character described, the combination of a roller, a plate resting upon said roller, said plate being adapted to be connected to a signal, said plate being adapted to be depressed so as to ride over said roller and operate the signal, springs engaging said plate for yieldably holding the same in a set 55 position, said plate having a longitudinally extending concaved portion, whereby as the plate is depressed the flange of a wheel fitting in said concaved portion will hold said plate against side displacement, plates positioned beneath said first-mentioned plate 60 and having sockets formed therein, springs carried by said sockets, whereby said springs will be held against displacement, said springs engaging said first-mentioned plate, thereby yieldably retaining said first-mentioned plate in a set 65 position, and said first-mentioned plate having a longitudinally extending concaved portion adapted to receive the flange of a wheel, whereby when said first-mentioned plate is depressed it will be 70 held against side displacement.

In testimony whereof I hereunto affix my signature.

EDGAR FOSTER.
